Attorneys.

By

UNITED STATES PATENT OFFICE.

ROBERT A. RASH, OF PETERSBURG, VIRGINIA, ASSIGNOR OF ONE-HALF HIS
RIGHT TO TAPPEY & STEEL, OF SAME PLACE.

IMPROVEMENT IN RAILWAY-SWITCH STANDS.

Specification forming part of Letters Patent No. **147,169**, dated February 3, 1874; application filed
December 22, 1873.

To all whom it may concern:

Be it known that I, ROBERT A. RASH, of Petersburg, in the county of Dinwiddie and in the State of Virginia, have invented certain new and useful Improvements in Railroad-Switch Stands; and do hereby declare that the following is a full, clear, and exact description thereof, reference being had to the accompanying drawings and to the letters of reference marked thereon, making a part of this specification.

The nature of my invention consists in the construction and arrangement of a railroad-switch stand which will prevent the liability of the switch being left open, or on the wrong side track, as will be hereinafter more fully set forth.

In order to enable others skilled in the art to which my invention appertains to make and use the same, I will now proceed to describe its construction and operation, referring to the annexed drawing, in which—

Figure 1 is a rear elevation of my switch-stand. Fig. 2 is a side elevation, and Fig. 3 a transverse vertical section, of the same. Fig. 4 is a plan view of the stand, and Fig. 5 is a front view of the slide.

A represents the stand, of any suitable dimensions, to which is pivoted the shifting-lever B. This lever is provided with a cap, C, to protect the parts from water and ice. D represents the lock. E is a slide, moving upon the shifting-lever B, and to which is attached the bolt a and tongue b. The stand A is provided with a flange, d, in which are three holes, e, f, and g, to receive the bolt a in each position of the lever, or for each track, respectively.

The tongue b moves in a recess in the face of the cap C, so as to present an even surface with the inner part thereof, and is provided with a hole, h, which comes immediately opposite the lock-bolt i, and a corresponding hole in the cap C when the slide E is moved down in position.

The lock D is so constructed that the key cannot turn entirely around, and hence cannot be withdrawn, except when the bolt is out, or is locked.

Now, it will be seen that, when the shifting-lever B is brought over to either side of its

central or proper position, the lock D cannot be locked, because the bolt i will be against the face of the cap C, and, consequently, the key cannot be withdrawn.

It will also be observed that, when the slide E, with the bolt and tongue, is raised up, that portion of the tongue b which extends below the lock-bolt i will then present an even surface, with no hole, which will prevent the locking and withdrawal of the key, even in the center position on the main track, unless the bolt a be down in the hole. It must be set for the main track and bolted before the switchman can get his key.

When it is locked in the center position on the main track, the lock-bolt i passes through the tongue b, which prevents the slide E, with its bolt and tongue, from being raised up, while the bolt a, passing through the flange b, sustains the strain, and prevents the shifting movement of the lever.

The bolt a drops into the holes e or f in the flange d, to hold the lever in position while on the side tracks; but, those positions being only temporary, it does not require to be locked there.

The switchman does not leave the switch until he sets it on the main track, and gets his key.

Having thus fully described my invention, what I claim as new, and desire to secure by Letters Patent, is—

1. The combination, with the stand A, of the cap C, attached to the track-shifting lever B, and the slide E, with the bolt a and tongue b, having hole h, all constructed substantially as and for the purposes set forth.

2. The combination of the stand A, with its flange d, having holes e f g, the shifting-lever B, cap C, slide E, with bolt a and tongue b, and the lock D, with bolt i, all constructed and arranged to operate substantially as and for the purposes herein set forth.

In testimony that I claim the foregoing, I have hereunto set my hand this 27th day of November, 1873.

ROBT. A. RASH.
